Hanson & Hanson

UNITED STATES PATENT OFFICE.

JOHN W. GRANGER, OF PHILADELPHIA, PENNSYLVANIA.

NEEDLE.

Application filed January 6, 1920. Serial No. 349,675.

To all whom it may concern:

Be it known that I, JOHN W. GRANGER, a citizen of the United States, residing in Philadelphia, Pennsylvania, have invented 5 Needles, of which the following is a specification.

This invention relates to sewing machine needles of the easy-threading type, which are characterized by having an opening into 10 the eye and an elongated guide element parallel with the needle stem or body for directing the thread through this opening into the eye, and one object of my invention is to provide a needle of this type with a novel 15 form of thread guide especially designed to avoid catching or splitting of the thread when it is attempted to introduce it between said guide and the stem.

Another object of the invention is to provide a needle with a novel construction of 20 stem or body and thread guide designed especially to prevent cutting of the thread at the time of its passage into the eye, and also to provide a needle whose body shall be 25 of a section such as will permit of its passage through the material operated on with less friction than has hitherto characterized needles of the type noted.

The invention further contemplates the 30 provision of a needle of the type noted which shall have a thread guide of such form and disposition as shall prevent its being permanently sprung or bent away from the stem;—the construction being particularly 35 designed to prevent the escape of the thread from the eye or its injury during tacking.

These objects and other advantageous 40 ends I attain as hereinafter set forth, reference being made to the accompanying drawings, in which,

Fig. 1 is a side elevation of a needle embodying my invention;

Fig. 2 is an enlarged transverse section on the line 2—2, Fig. 1;

Fig. 3 is a side elevation of a modified form of needle.

Fig. 4 is a fragmentary elevation on a larger scale than Fig. 3, illustrating the detail construction of the free end of the 50 thread guiding element;

Fig. 5 is a transverse section on the line 5—5, Fig. 4;

Fig. 6 is a side elevation of a needle embodying a second modification of my invention;

Fig. 7 is an enlarged fragmentary elevation of a portion of the needle shown in Fig. 6:

Fig. 8 is a transverse section of the line 8—8, Fig. 7; 60

Fig. 9 is a fragmentary side elevation showing the preferred construction of the thread guiding member adjacent the eye;

Fig. 10 is a transverse section on the line 10—10, Fig. 9; 65

Fig. 11 is a side elevation of another form of my needle; and

Fig. 12 is a longitudinal section of a needle having a special form of thread guide.

In Fig. 1 of the above drawings 1 represents the shank or head of the needle which has a stem or body portion 2 of reduced diameter and a point 3. Adjacent the portion where said point joins the stem, the latter is formed with a longitudinal cut or slit extended rearwardly from a point parallel with and usually to one side of its center line, and then at an acute angle thereto so as to divide the forward end of the stem into two parts. One of these parts has formed 70 in it an eye 4 into which the slit or cut opens, and the rear end of said part is extended toward the shank 1 in the form of an elongated relatively thin flexible rod 5 constituting a thread guide. This lies parallel and 75 partly within an elongated, channel shaped slot or in the stem recess, and extends to within a short distance of the shank where its free end portion 6 is turned at right angles and is curved circularly around the 80 stem. This portion is free to move transversely of the needle to a limited extent and its extremity projects from the stem in a line substantially tangent thereto so as to form 85 a converging thread directing channel. 90

The guide rod 5 is preferably of substantially circular section and when it is desired to introduce a thread into the eye, said thread is held in a position substantially parallel to the center line of the needle and is 95 placed between the projecting extremity of the guide rod and the stem. From this channel it is drawn between the part 6 and the stem 5, around the latter until it lies between the main portion of said guide rod 100 and the stem, from whence it may be drawn toward the point until it finally passes into the eye 4.

In view of the circular section of the 110 guide rod and of the fact that it lies in

the longitudinal slot of the needle stem so as to project but a slight distance beyond the surface thereof, there is a negligible friction with the material through which 5 the needle is operated under working conditions. Moreover with the peculiar arrangement of the extremity of the guide rod relatively to the stem, the thread to be placed in the eye is entered between the stem and 10 said rod in such a manner that there is a negligible chance of its being caught upon the end of the rod and split or cut. Moreover, since the free end of the guide rod is held by being curved around the stem, its 15 body portion cannot be sprung laterally away from said stem by the careless introduction of the thread into the eye so far as to break or cause permanent bending of said rod, as would be the case if its end 20 could be bodily pulled away from the stem for any considerable distance. By the peculiar construction of the needle point 3 and the adjacent portion of the stem, this 25 part of the needle is not objectionably weakened by the cut or slit for the introduction of the thread, since it is noted that there are equal thicknesses of material on both sides of the eye.

While in that form of my invention 30 shown in Fig. 1 the cut or slit in the forward end of the stem may and usually does extend forwardly beyond the eye 4, in that form of the needle shown in Fig. 3 the guide rod 5^a is connected integrally with the stem 35 immediately adjacent the point without being materially enlarged as in the other form of my invention. Moreover in order to prevent escape of the thread from the eye or its injury during the operation of 40 tacking, the forward end of the guide rod is deflected into the eye as shown in detail at 7 in Figs. 9 and 10, so that it tends to hold the thread away from the adjacent walls of the eye and thus prevent its escape 45 as well as its abrasion or cutting. In this particular case the free extremity of the guide rod is bent through approximately 180 deg. or returned upon itself as shown at 8, so as to provide a curved wall for one 50 side of the entrance channel whereby the thread is directed between the stem and said rod.

If desired I may modify the form of the 55 guide rod shown in Figs. 1 and 2 in the manner illustrated in Figs. 6, 7 and 8, where its extremity after being carried around the stem 2, is turned through 180 deg. and folded back upon itself so as to prevent possibility of a thread being split or cut by 60 its square end.

In Fig. 11 I have shown another form of 65 my invention in which the guide rod is formed with a loop or lateral U-shaped projection 10 at that portion of the stem immediately adjacent the head or shank 1 and

in this case said rod is continued beyond the loop in a longitudinally extending groove formed in the shank to such a depth that it is completely below the cylindrical surface thereof. This loop is designed to receive the end of the thread which is to be inserted in the eye 4 and thereafter said thread is moved downwardly toward the point between the stem 2 and the guide rod 5 which is sprung outwardly until it enters 75 the eye.

If advisable or necessary to prevent accidental springing of the guide rod 5 too far away from the stem of the needle, I may provide a hole 12 through the shank adjacent its junction with the stem and carry the extremity of the guide rod therethrough, bending it substantially at right angles on the opposite side of the needle as indicated at 13. By this means the pulling of said 85 rod away from the stem to an injurious extent is effectually prevented.

From the above description it will be appreciated that I have provided a form of 90 needle which may be manufactured on a commercial scale and whose arrangement of parts is such as to facilitate quick and convenient threading. Moreover, the thread guiding rod is of such construction and so mounted that it not only is practically impossible for its extremity to cause splitting or cutting of the thread but it is likewise so arranged that it cannot be easily broken or permanently sprung away from the stem. The formation of the eye and of the adjacent parts of the needle is such that the latter is not appreciably weakened by the presence or attachment of the thread guiding rod, for the latter is so disposed adjacent the eye as to prevent escape of the 100 thread therefrom and also cutting thereof even under the extreme conditions existing when the machine in which the needle is mounted is employed in tacking.

I claim:—

1. A sewing machine needle having a shank, a stem and a point, said stem being formed adjacent its junction with the point with a longitudinal cut extending rearwardly from a point parallel and to one side of its center line and bent at an acute angle therewith so as to divide the forward end of the stem into two parts of which one has formed in it an eye into which the cut opens, the rear end of said part being extended toward the shank in the form of a relatively thin flexible rod passing around the stem and formed to constitute a thread guide.

2. A needle consisting of a shank, a stem, and a point, and having an eye with an opening thereinto; with a guide rod connected to the forward end of the needle and extending parallel with the stem toward the shank thereof, the free end of said rod 130

being extended around the stem of the needle to prevent its excessive lateral movement.

3. A needle consisting of a shank, a stem, 5 and a point, and having an eye with opening thereinto; with a guide rod connected to the forward end of the needle and extend-

ing parallel with the stem toward the shank thereof, the free end of the rod being formed to present a curved surface for directing a thread between it and the stem and being curved around the needle to prevent its excessive lateral movement. 10

JOHN W. GRANGER.
